REFRIGERANT DISTRIBUTOR

Frank C. Ort, Marcellus, N. Y., assignor to Carrier Corporation, Syracuse, N. Y., a corporation of Delaware

Application May 14, 1948, Serial No. 27,024

4 Claims. (Cl. 62—126)

1 This invention relates to a refrigerant distributor for refrigeration systems and more particularly to a liquid refrigerant distributor for supplying liquid refrigerant to separate circuits of a direct expansion evaporator.

In distributors heretofore provided, it is extremely difficult to assure adequate and uniform distribution of refrigerant to the various evaporator circuits when the refrigerant requirement of each circuit is small due to light loading of the evaporator. This is a frequent occurrence in low temperature applications. To eliminate inefficiencies in the refrigeration system, it is essential that each evaporator circuit be provided with a proportionate supply of refrigerant at all times.

The chief object of the present invention is to provide a refrigerant distributor for a direct expansion evaporator which assures steady and uniform distribution of refrigerant to separate circuits of the evaporator under all loading conditions of the evaporator.

An object of the invention is to provide a refrigerant distributor including a member adapted to reduce the velocity and turbulence of refrigerant entering the distributor before its distribution to the various circuits of the evaporator thus assuring uniform distribution to separate circuits.

A further object is to provide a refrigerant distributor capable of distributing refrigerant uniformly to separate evaporator circuits under conditions of light load of the evaporator.

A still further object is to provide a refrigerant distributor which may be manufactured at low cost. Other objects of my invention will be readily perceived from the following description.

This invention relates to a distributor for a refrigeration system which comprises a casing having an inlet therein through which refrigerant is discharged within the casing. Tubes extend within the casing to receive refrigerant therein, each tube supplying refrigerant to a separate circuit of the evaporator of the refrigeration system. A baffle is disposed within the casing between the tubes and the inlet. Entering refrigerant strikes the baffle thereby separating to some extent gaseous refrigerant from the liquid refrigerant. Liquid refrigerant so separated may pass through openings in the baffle to the tube chamber of the distributor. The baffle in effect separates refrigerant into two streams flowing toward the end walls of the casing. The refrigerant streams strike the end walls of the casing with sufficient velocity which, in addition to the abrupt change of direction, causes further separation of gaseous and liquid refrigerant. The liquid refrigerant passes around the ends of the baffle into the tube chamber. The velocity and turbulence of entering refrigerant is thus reduced permitting the separation

of gaseous from liquid refrigerant and assuring equal distribution of liquid refrigerant to the various circuits of the evaporator. Gaseous refrigerant flows around the ends of the baffle and distributes itself uniformly to the various tubes.

The attached drawing illustrates a preferred embodiment of my invention in which

Figure 1 is a diagrammatic view of a refrigeration system including the distributor of my invention;

Figure 2 is an isometric view of the distributor partially broken away to disclose the interior thereof;

Figure 3 is a sectional view longitudinally of the distributor; and

Figure 4 is a sectional view laterally of the distributor.

Referring to the drawing, there is shown the usual refrigeration system including a compressor 2 connected by line 3 to a condenser 4. Refrigerant flows from condenser 4 to a receiver 5; refrigerant flows from receiver 5 through liquid line 6 to a thermal expansion valve 7 or other suitable expanding means. Refrigerant from expansion valve 7 flows through line 8 to liquid distributor 9 which distributes liquid refrigerant uniformly to the various circuits of evaporator 10. Refrigerant, after its passage through the various circuits of evaporator 10, is collected in a header 11 and returned through suction line 12 to compressor 2. The expansion valve 7 is regulated by means of a thermal sensitive bulb 13 disposed adjacent suction line 12.

Distributor 9 consists of a cylindrical casing 14, the ends of the casing being closed by means of closures 15, threaded or welded thereto. Tubes 17 extend within casing 14 and are connected to the various circuits of evaporator 10 to permit liquid refrigerant within the distributor to be distributed uniformly to the various circuits of the evaporator.

A baffle 18 is disposed within casing 14 and serves to separate casing 14 into two chambers, 19 and 20, casing 14 contains an inlet 21 through which refrigerant supplied through line 8 enters entrant chamber 20. Baffle 18 extends longitudinally of casing 14, its ends being spaced from the closures 15 as shown at 22 and 23. So disposing baffle 18 permits refrigerant to flow around its ends into tube chamber 19.

Baffle 18 is provided with flanges 24 and 25 to assist in securing the baffle in desired position within the casing, such flanges permitting a tight fit to be secured. Openings or slots 26 are formed in flange 25 for a purpose hereinafter described. It will be appreciated other forms of openings may be employed if desired. Baffle 18 may be soldered or welded to assure that it retains desired position within the casing 14. If desired, baffle 18 may be formed of suitable resilient flex-

ible metal; in such case, baffle 18 may be biased to assure that flanges 24 and 25 are urged strongly against the interior wall of the casing thereby holding the baffle in desired position.

Refrigerant is discharged from line 8 into casing 14 through inlet 21. Velocity of entering refrigerant is such that it strikes baffle 18 with considerable force thus creating turbulence in the refrigerant and causing some portion of the gaseous refrigerant to separate from the liquid refrigerant. Liquid refrigerant so separated may flow through openings 26 into tube chamber 19. Baffle 18 serves to divide the stream of entering refrigerant into separate streams flowing toward the end walls of casing 14. Such streams of refrigerant strike the end walls of casing 14 formed by closures 15 with considerable force thus again dissipating velocity of flow and creating turbulence of refrigerant thereby separating gaseous refrigerant from liquid refrigerant. The liquid refrigerant so separated passes around the ends of baffle 18 into tube chamber 19 and is distributed uniformly to the various tubes 17 thus permitting uniform distribution of liquid refrigerant to the various circuits of evaporator 10. Gaseous refrigerant separated from the liquid refrigerant in chamber 20 flows around the end walls of baffle 18 and distributes itself uniformly to the various tubes 17.

My invention provides a novel refrigerant distributor for direct expansion evaporators containing a plurality of circuits which may be made at low cost. The distributor so provided assures uniform and adequate distribution of refrigerant to the various evaporating circuits even under conditions of light load of the evaporator such as occurs frequently in low temperature refrigeration applications. Provision of the baffle assures that the velocity and turbulence of liquid refrigerant entering the distributor is utilized to separate gaseous from liquid refrigerant. The velocity and turbulence of entering refrigerant is reduced or dissipated by striking the baffle and the end walls of the casing thus assuring uniform distribution of liquid refrigerant to the various tubes leading to the circuits of the evaporator.

While I have described a preferred embodiment of my invention, it will be understood my invention is not limited thereto since it may be otherwise embodied within the scope of the following claims.

I claim:

1. In a distributor for a refrigeration system, the combination of a horizontally extending casing having an inlet therein through which refrigerant enters the casing, tubes extending upward within the casing to receive refrigerant therein, each tube supplying refrigerant to a separate circuit of the evaporator of the system, and a horizontally extending baffle disposed within the casing extending longitudinally thereof between the tubes and the inlet, said baffle having upper and lower flanges, said flanges fitting against the interior wall of the casing, said lower flange having openings therein to permit flow of liquid refrigerant from one side of the baffle to the opposite side thereof.

2. In a distributor for a refrigeration system, the combination of a horizontally extending casing having a refrigerant inlet, a plurality of tubes extending upward within the casing to receive refrigerant therein, each tube supplying refrigerant to a separate circuit of the evaporator

65

of the system and a horizontally extending baffle disposed between said tubes and the inlet within the path of entering refrigerant, said baffle extending longitudinally of the casing and being spaced from the end walls of the casing, said baffle having openings therein to permit refrigerant to flow from one side of the baffle to its opposite side, entering refrigerant striking the baffle to separate some portion of gaseous refrigerant from the liquid refrigerant, said baffle being so constructed and arranged as to direct streams of refrigerant toward both end walls of the casing to strike the same, again creating turbulence while reducing the velocity of the streams of refrigerant to separate gaseous from liquid refrigerant.

3. In a distributor for a refrigeration system, the combination of a horizontally extending casing having a refrigerant inlet, closures sealing the ends of the casing, tubes extending upward within the casing to receive refrigerant therein, each tube supplying refrigerant to a separate circuit of the evaporator of the system, and a horizontally extending baffle extending longitudinally within the casing disposed between the tubes and the inlet and having a length less than the length of the casing to provide open spaces between the ends of the baffle and the closures sealing the ends of the casing, entering refrigerant striking the baffle with sufficient force to separate some portion of gaseous refrigerant therefrom, some portion of liquid refrigerant being free to flow through openings in the baffle to the tubes, said baffle being so constructed and arranged as to divide the greater portion of the refrigerant into streams flowing toward and striking the end closures to separate again gaseous from liquid refrigerant flowing toward the tubes.

4. In a distributor for refrigeration system, the combination of a horizontally extending casing having a refrigerant inlet, a plurality of tubes extending upward within the casing to receive refrigerant therein, each tube supplying refrigerant to a separate circuit of the evaporator of the system, and a horizontally extending baffle disposed between said tubes and the inlet within the path of entering refrigerant, said baffle having upper and lower flanges, the flanges being flexed against the interior wall of the casing to retain the baffle in desired position, said baffle extending longitudinally of the casing and being spaced from the end walls of the casing, entering refrigerant striking the baffle to separate some portion of gaseous refrigerant from the liquid refrigerant, said baffle being so constructed and arranged as to direct streams of refrigerant towards the end walls of the casing to strike the same, again creating turbulence while reducing the velocity of the streams of refrigerant to separate gaseous from liquid refrigerant.
